By his Atty.

D. Reigart.

United States Patent Office.

GEORGE W. MYERS, OF HARTLETON, PENNSYLVANIA.

Letters Patent No. 78,002, dated May 19, 1868.

IMPROVEMENT IN KNIVES FOR REMOVING THE SKINS FROM ANIMALS.

The Schedule referred to in these Letters Patent and making part of the same.

TO ALL WHOM IT MAY CONCERN:

Be it known that I, GEORGE W. MYERS, of Hartleton, Union county, State of Pennsylvania, have invented an Improved Knife for Cutting the Hides off of Cattle; and I do hereby declare the following to be an exact description thereof, reference being had to the accompanying drawings, and to the letters of reference marked thereon, making a part of this specification, in which—

Figure 1 represents a perspective view of the knife.

Figure 2 a cross-section.

The nature of my invention consists in the fine-bladed knife, tapering to a point, with an adjustable similar blade on the one side, operating on the other blade by screw-heads moving in a slot. This outside blade is rounding on the edges, and this rounding edge is for the purpose of preventing the sharp edge of the knife from cutting the hide, as many of the most valuable hides are injured by cutting, thereby involving serious loss to tanners.

A represents the blade of the knife, B the handle, C the additional blade or guard, attached to the side of the blade of the knife. This blade is adjustable by two slots, D D, in which screw-heads, E E, attached to the knife-blade, operate in the slots, and by which the outside blade C is moved back or forward from the sharp edge of the knife-blade, so as to regulate the depth of the cutting, and prevent the sharp edge from cutting the hide.

I am aware that a razor with a guard attached has been used, but this I do not claim; but

What I claim as my invention, and desire to secure by Letters Patent, is—

The combination and construction of the guard C, that is movable and adjustable with the knife-blade A, as herein described, and for the purposes set forth.

GEO. W. MYERS.
